[57] CLAIM

The ornamental design for the beverage dispenser, as shown and described.

DESCRIPTION

FIG. 1 is a top, front, and left side perspective view of a beverage dispenser showing my new design;

FIG. 2 is a left side elevational view thereof;

FIG. 3 is a right side elevational view thereof;

FIG. 4 is a front elevational view thereof;

FIG. 5 is a top plan view thereof;

FIG. 6 is a rear elevational view thereof;

FIG. 7 is a bottom plan view thereof;

FIG. 8 is a top, front, and left side perspective view of a modification of my new design for a beverage dispenser;

FIG. 9 is a front elevational view thereof; and,

FIG. 10 is a right side elevational view thereof.

For this modified form of my new design, the left side elevational view is identical to FIG. 6, the top plan view is identical to FIG. 5, the rear elevational view is identical to FIG. 3, and the bottom plan view is identical to FIG. 7.
